UNITED STATES PATENT OFFICE

MAXEY C. COOPER, OF DETROIT, MICHIGAN

WALL PAPERING MACHINE

Application filed May 22, 1930. Serial No. 454,761.

My invention relates to wall papering machines, more particularly to wall papering machines adapted for trimming and pasting the paper and for facilitating the hanging thereof, and it consists of the construction, combinations and arrangements herein shown and described.

An object of my invention is to provide a light portable mechanism which will contain the wall paper and trim and paste the same during the papering operation.

A further object of my invention is to provide a device of the type described which will be adapted to be positioned for papering the walls, ceiling and the border strips customarily placed on the wall.

A further object of my invention is to provide a device of the type described which will regulate the amount of paste on the papers to any desired thickness.

A further object of my invention is to provide a device of the type described which has few parts, is simple to manufacture and does not get out of order easily.

Other objects and advantages will appear as the specification proceeds and the invention will be more particularly defined in the appended claims.

My device is illustrated in the accompanying drawings, forming a part of this application, in which:

Figure 1 is an elevational view of my device in one operative position;

Figure 2 is an elevational view of my device in another operative position;

Figure 3 is an elevational detail view of a portion of the device;

Figure 4 is a longitudinal sectional view, with parts thereof shown in elevation of a portion of the detail shown in Figure 3;

Figure 5 is a transverse sectional view of a portion of the detail shown in Figure 3;

Figure 6 is a detail elevational view of a portion of the part of the device shown in Figure 3;

Figure 7 is a detail perspective view of a portion of the device shown in Figure 3;

Figure 8 is a detail perspective view of a portion of the device shown in Figure 3;

Figure 9 is a sectional view on the line 9—9 of Figure 3;

Figure 10 is a sectional view, on line 10—10 of Figure 1;

Figure 11 is a detail sectional view, with parts shown in elevation for clearness of illustration of a portion of the device.

In carrying out my invention, I may make use of an ordinary step ladder 1, such as commonly used by workmen engaged in wall-papering. My device is adapted to be mounted upon either the top step of said step ladder as shown or upon any other suitable portion of said step ladder by a bracket mounting means generally indicated at 2. This mounting 2 is adapted to support the wall papering machine suspension means 3 for suspending the machine 4 or to support said suspending means 3 in an alternative position for the positioning of the wall papering machine 4 to perform different papering operations.

The wall-papering machine proper 4 consists of a pair of end plates 5 and 6 joined together by means of rods 7 which are made integral with said end plates by any suitable means. These end plates provide bearings in which the various rotatable and movable portions of the wall-papering machine proper are journaled.

Secured in the lower portion of this wall-papering machine proper 4 between the end plates 5 and 6 by rivets, bolts or other suitable fastening means is the paste chamber 8 consisting of an ordinary rectangular box-like member as appears most clearly in Figures 5, 6, and 7.

For filling this paste box or container 8 with paste I provide a suitable duct 9 extending from one of the end walls of the wall-papering machine proper, as shown in this embodiment. This duct 9 limits the ca-

pacity of the paste box 8 to a point 10 coincident with its upper extremity. A suitable door 11 closes this duct against the admission of extraneous matter and secures the paste in the box. This door 11 may be spring-pressed or maintained shut in any other suitable manner, if desired.

For the exit of the paste from the paste box when it is desired an outlet bore 12 may be formed in the opposite end or in the same end of the paste box for communication with the similar bore formed in one of the end plates to provide a suitable outlet from the paste box. A plug 13 engages in this bore for closing the same and preventing emission of paste when undesired. This plug 13 may be threadedly engaged with the bore or secured therein by any other suitable fastening means. The body portion of this plug is made of any suitable transparent material 14 which permits the observation by an operator of the amount of paste in the box thereby forming a simple and efficient indicating means for this purpose.

For cooperation with the wall paper for performing the wall-papering operation I provide a paste roller 15 which is journaled for rotation in the box by any suitable means. In this embodiment however I illustrate the use of members which I term side plates 16 having bearings 17 at their substantial centers for journaling the ends 18 of this paste roller 15. These end plates 16 are connected to the walls of the paste box and are maintained in relatively fixed position by any suitable means. They are made sufficiently wide in this showing to completely span the space between the end of the roller 15 and the end of the paste box 8 to prevent the insertion of paste or other adhesive material utilized in the paste box into said box through said space and to prevent splashing of the paste from said box. It can easily be understood that the use of this space for the insertion of paste might lead to splashing of paste over parts which should be kept clean at all times to insure a successful operation of the machine.

In the upper portion of the end plates 5 and 6 bearing slots 19 are provided for adjustably journaling a roll 20 upon which the wall paper 21 is rolled. The ends of the journals of this roll 20 are threaded for the reception of threaded milled nuts 22 used for permitting an operator to adjustably position the roll 20 within the slots 19 and to retain said roll 20 in said adjustable position for the reception of wall paper rolls of various sizes. These milled nuts 22 by engagement with the walls 5 and 6 provide for retention of the roll 20 in any desired position along the slot 19, as is easily understood.

For preventing over-travel as well as backlash of the wall paper relative to the roll 20 when the same is withdrawn therefrom by an

operator, I provide a stationarily positioned roll 23 journaled in the end plates 5 and 6 in any convenient or suitable position relative to the roll 20. This roll 23 cooperates with a spring pressed or resiliently urged roller member 24 for maintaining a slight pressure on the paper for the purpose heretofore set forth.

The roller 24 is journaled in the swingably or pivotally mounted bracket arms 25 and 26 which are rotatably journaled on the shaft 27. The coil springs 28 and 29 secured to the shaft 27 as indicated at 30 and 31 respectively cooperate at their opposite extremities with the bracket arms 25 and 26 to normally urge said bracket arms 25 and 26 to press the roller 24 into engagement with the roller 23.

For permitting an operator to adjust the amount of pressure exerted by the roller 24 on the paper between said roller and the roller 23, I provide a small lever handle 32 which is fixedly secured to the shaft 27 on the outside of either of the plates 5 and 6. This small lever handle 32 is resiliently forced outwardly by means of a coil spring 33 engageable between said crank lever and the adjacent end plate. This spring maintains the lever in any adjusted angular position. Suitable stops 34 limit excess movement of the roller 24.

For guiding the wall paper through the machine during the insertion thereof and during the operation I provide a pair of plates 35 and 36 positioned on opposite sides of the path taken by said wall paper after it leaves the rollers 23 and 24 and adapted for the reception of said wall paper therebetween. These guide plates 35 and 36 may be fastened in the end plates of the wall papering machine proper or they may be adjustably secured therein by any suitable means not shown. The plates may also be formed in any desired fashion to secure the function of properly alining the paper during its operation. In this construction, however I have shown one of them made in simple rectilinear form while the other 36 has oblique portions 37 and 38 at its extremities to engage and assure proper alinement of the paper for entry into the space between the plates. The operation of this part of the device is similar to the operation of a typewriter when the paper is inserted between the roll.

The paper 21 after it passes between the guide plates 35 and 36 moves about the idler 39 which may be fixedly positioned in the end plates or adjustably secured therein, as desired.

For cooperation with the idler 39 to perform the cutting or trimming operation I mount loosely on the shaft 27 the trimmer supporting brackets 40 adapted to pivotally mount and support the trimmers 41. These brackets 40 are shown as comprising

two arms 42 which provide a pair of bearings 43 for engagement with the said shaft 27. A single arm 44 on said brackets projects downwardly for rotatably supporting a shaft 45 of the cutters 41.

These cutters comprise essentially a body portion or hub 46 integrally secured to the shafts 45 for rotation therewith and provided with apertures or bore holes in one of the faces 47 thereof for mounting of the cutter blade 48. This cutter blade 48 also provides apertures within its face for the reception of bolts or other suitable fastening means therein for engagement with the apertures in the face of the body portion 46 for securing said cutters in place. Any other suitable mounting means might be utilized for securing these cutting blades 48 in position. It will be noted that in this embodiment the body portions 46 are of lesser radial extent than the blades 48.

For resiliently urging the cutters 41 into engagement with the paper passing therebetween and the roll 39 I provide the resilient or spring means shown at 49. These springs are stopped or fixed at one of their extremities by engagement of said extremity with the plate 36 as appears at 50. The other ends of these springs engage the portion 51 of the bracket 40 for normally urging the same about the shaft 27 toward the roll 39.

At the opposite side of the paste roller 15 for cooperation with the roller 39 for guiding the wall paper over the roll 15 for performing the pasting operation I provide an idler 52 which may be fixedly journaled in the plates 5 and 6. In this embodiment the roller 52 is adapted to be adjustably positioned in a slot 52^a and retained therein by a retaining bearing means shown at 52^b and which may be mounted on the end plates by means shown at 52^c. A milled screw 52^d permits retention of the bearing member 52^c at desired points in slot 52^a. This idler 52 is particularly formed to guide the paper from the machine by providing on the periphery thereof a series of circumferentially-extending corrugations comprising the ridges 53 and the hollows 54. By engagement with these ridges and the hollows 54 the paper is secured in its proper path during withdrawal from the machine. This idler 52 cooperates with an oppositely disposed idler 55 in a manner that will be later described to further assure proper guiding of the paper during its exit from the machine. The roller 55 is positioned by the aperture 56 from which the paper is withdrawn and over a trough 57 adapted to convey any paste or other adhesive matter dropping from the roll 55 back into the paste box 8. For regulating the amount of paste adhering to the paste roll 15 during the pasting operation I provide a brush or scraper 58 supported by a bracket 59 for rotation with a shaft 60 journaled in the end plates 5 and 6 in any suitable fashion. This

brush may be adjusted for close or distant cooperation with the paste on the roll 15 at the will of an operator by a lever 61 fixedly mounted for rotation with the shaft 60. A resilient spring 62 engageable between the end wall and the lever 61 serves to retain said brush in the adjusted position. Suitable stops 63 are provided as in the case of lever 33 for limiting movement of this lever 61.

For allowing access to the interior of the machine for permitting measurement of the width of the paper as well as for any other purposes desired the wall papering machine proper 4 is equipped with a door 64 hinged as shown at 65 to the end plates 5 and 6 and secured in closed position by any suitable latch means such as that indicated at 66. A bottom or base plate 67 being integral with or secured between the end plates 5 and 6 completes the housing structure of the wall papering machine proper. This base or bottom plate 67 is provided with a cutaway portion 68 which is adapted to be positioned behind the paste box 8 between the door 64 and the rear wall of said paste box. It is through this cutaway portion 68 that the trimmed or cutaway portions 69 of the wall paper 21 exit upon the machine.

For supporting the wall papering machine in a suspended position when the machine is positioned for certain operations I provide a pair of longitudinally extending rods 70 and 71 which extend between the end plates 5 and 6 and are secured therebetween in any desired manner. These rods 70 and 71 pivotally mount thereon at each of their extremities sets of links 72 and 73 respectively. Pivotally interconnecting the links of set 72 and 73 is a roller 74 which is utilized in one of the operations to guide the paper and which may be further utilized as a bail member to be used in the transportation of the wall papering machine proper.

The links 72^a and 73^a are provided with elongated slots engageable about the rod 71 and a knurled or milled nut 71^a is secured to the ends of the rod 71 for frictional engagement with the links 72^a and 73^a adjacent said slot to secure said links in variable adjusted positions as will be later described. Additional links 75 are pivotally connected to the roller 74. These links 75 provide eyelets 76 for the engagement therewith of hook members 77 used in the suspension of the device.

These hook members 77 may be of any suitable or desired construction, but as shown they comprise a rigid hooking member 78 and a resilient member 79 cooperating therewith for performing the hooking operation in the well known manner. The slot 80 provides means for engagement with straps as will be described.

The wall papering machine suspension and mounting means 3 comprises a pair of end plates 81 and 82 connected by rods 83 or other

suitable spacing means not shown and adapted to journal therein an automatic reel 84. This automatic reel may be constructed in any suitable fashion but is shown as being 5 made in the form of an ordinary shade roll having a spring (not shown) therein and having its shaft retained against movement in one direction by pawls 85 adapted for engagement with the shaft 86 therein in a manner 10 easily understood.

Suitable disks or collars 87 are provided at each extremity of the roll 84 for engagement with straps 88 for securing the same against axial movement along the roll. These straps 15 88 are connected to the hooks 77, as clearly shown in Figure 3 and are maintained in spaced relation by means of a bracing bar or rod 89.

For maintaining the wall papering machine 20 suspension and mounting means 3 in position during one of the operative positions of the device I mount on said suspension and mounting means 3 a plate 90 on which I position a block 91 having projecting therefrom 25 a stud 92. This stud 92 is secured in position in the block 91 by means of bolts or any other suitable means. It carries a collar 93 having an aperture 94 therein. This collar 93 is provided for a purpose which will soon appear.

For retaining the stud 92 in its various positions to variably position the suspension and mounting member 3 during certain operations, said stud 92 is provided with diametrically extending bores 95, 96, which are 35 adapted for engagement with a bolt 97 which is equipped for release by the latch means generally indicated at 98.

This latch means comprises a longitudinally 40 extending member 99 integral with said bolt and having positioned thereon a resilient compression member 100 which has one end connected to the longitudinally extending member 99 while the other abuts a stop 45 or shoulder 101, as appears most clearly in Figure 3. A similarly formed stop or shoulder 102 provides means for limiting outward movement of the bolt as well as aids in the guiding of said bolt during its operation. 50 The operating handle 103 permits compression of the spring upon withdrawal of the bolt by engagement of the operator with said handle or by other means.

The bolt-latch and associated members are 55 mounted on an arm 104 which as appears most clearly in Figure 1 is adapted to project horizontally from the bracket support 2 to support the wall papering machine proper and its suspension and mounting means with respect to said bracket. This rod 104 loosely 60 engages through an eyelet 105 of a screw member 106 mounted on a collar 107 secured to the vertical post 108 which post is adjustably mounted in the clamping bracket. The 65 rod 104 is supported by the arms 109 which

are pivotally secured to the post 108 and provide at their outer extremities a saddle 110 which receives the rod 104 therein. It can be easily understood that these arms 109 and associated saddle 110 and the screw member 70 106 provide a two point suspension for the horizontally extending rod 104 permitting the same to be slid longitudinally through said eyelet and said saddle for adjustably 75 positioning the wall-papering machine as desired.

When it is desired to position the machine as shown in Figure 2 for certain operations, such as papering the ceiling, the locking slots 111 in the suspension and mounting means 3 are utilized. These locking slots 111 are 80 adapted for engagement with the studs 112 or with the ends of the shafts 7 which may be constructed to project beyond the end plates 5 and 6 for securing the wall papering machine proper in fixed position on the suspension and mounting device 3. With the parts thus positioned the aperture 94 in the collar 93 is utilized for the reception of a bolt 113 which is engageable through said 85 collar and with the collar 107 for variable 90 positioning of said suspension and mounting member 3 about the post 108, when desired by an operator. Adjustment of said suspension and mounting means is secured by 95 means of the set screw 114 which projects through said collar 107 and engages an aperture 115 in the post 108.

The clamping bracket is adapted for 100 adjustably positioning the post 108 by means of apertures (not shown) in said post, through which a latch means 116 is adapted to project. This latch means 116 is similar to the latch means heretofore described in 105 connection with the stud 92 and need not be further described. The same is secured on top of the bracket 117 in fixed relation.

This clamping bracket 117 as will appear 110 from an examination of Figure 10 is provided with clamping members 117 which 115 clampingly engage a step ladder 1 or any other desired device on which it is wished to secure my device. These clamping members 117, as appears most clearly in Figures 2 and 3, comprise a pair of horizontally extending jaws 118 and 119 with screw-actuated clamp members 120 and 121 positioned in one of said jaws. These screw actuated clamp members 120 and 121 in cooperation with the 120 jaws thus provide an efficient clamping means for securing the entire device to any adaptable member as easily understood.

From the foregoing description, the use 125 and operation of my device is easily understood. When the operator desires to paper a wall he positions the machine as shown in Figure 1 by clamping the clamping bracket 2 to any suitable support, such as the step ladder 1 inserting the rod 104 through the saddle 120

110 and through the eyelet 105 of the screw member 106 carried by the post 108. The wall papering machine proper 4 as shown in said figure, when the machine is set up in this 5 form for operation, is suspended by the straps 88 from the automatic reel 84.

The operator may, if desired, by means of the latch 103 release the stud 92 and turn the 10 suspension and mounting means 3 to a desired position for operation of the device.

He may further position the device by drawing down upon or releasing for elevation the wall papering machine proper 4 by means of the automatic reel.

15 When the machine is properly positioned for the wall-papering operation he draws on the wall paper 21 manually or otherwise removes the same through the aperture 56. The paper during this operation is held under tension without backlashing or overtravel by means of the resiliently pressed roller 24 and the stationarily-positioned roller 23 and is cut or trimmed to the desired width by means of the cutters 41 resiliently

20 pressed into engagement with the paper as it passes about the stationarily-positioned idler 39. These cutters as heretofore set forth may be adjusted to any desired width and may be thrown to the outer extremities

25 of the shaft 27 out of engagement with the wall paper if desired. The trimmed paper then passes over the paste roller 15 while the trim 69 passes down through the aperture 68 and out of the machine. After the application 30 of the paste by the roller 15 the paper passes out of the apertures 56 of the machine between the rollers 52 and 55. The operator has then only to apply the paper in the usual fashion manually or otherwise.

35 When the operator desires to apply wall paper to the ceiling he positions the machine upon the top step of the step ladder as shown in Figure 2, as heretofore set forth, or upon any other suitable support. The stud 92 is

40 inverted from the operative position shown in Figure 1 with the collar 93 brought into engagement with the collar 107 which is stationarily positioned on the post 108. The stud 92 is integrally connected with the suspension and mounting means 3 and the same is supported on said stud 92 in the position shown in Figure 2. The wall papering machine proper 4 is then placed on top of the

45 inverted suspension and mounting means 3 with the studs 112 or the ends of the rods 7 whichever are utilized for the purpose being brought into engagement with the locking slots 111. The links 72^a and 73^a having slots

50 therein for cooperation with the milled nuts 71 and 71^a are then adjustably positioned in the desired position such as that shown in Figure 2. When so positioned the roll 74 which pivotally mounts the links, provides

55 means over which the paper may pass to

bring the same into engagement with the ceiling, as shown in Figure 2.

The operator may adjustably position the machine about the post 108 by means of the set screw 114 engageable through the collar 70 107 on said shaft 108.

The machine may be further adjusted as to its operative position by means of the latch 116 as heretofore set forth in connection with the operative position shown in Figure 1.

75 The operator then draws the paper from the machine as described in connection with the other operative position about the roll 74 if desired, the same being trimmed and pasted by means 4.

80 During the positioning of the machine for various operations as well as for transportation of the device the roll 74 may be used as a bail or handle for manual engagement by the operator for transportation purposes.

85 It is thus seen that I have provided a wall papering machine which is adapted for positioning in any desired place for operation by a user.

90 It is also seen that I provide a wall papering machine which is particularly and efficiently adapted to perform two major operations of wall papering, that is papering the walls and the ceiling.

95 It is further seen that I have provided a wall papering machine which trims the paper, applies the paste thereto, and is adapted to permit easy withdrawal of said paper from the machine in a most efficient manner.

I claim:

1. A wall papering machine comprising a member adapted to trim and apply the paste to the paper, a suspension member adapted to position said member in elevated and lowered positions during the operation, and means for adjustably positioning said suspension means at the will of an operator.

105 2. In a wall papering machine, means for trimming and applying the paste to the wall paper, and means for variably positioning said trimming and paste-applying means comprising an automatic reel, flexible members interconnecting said automatic reel and said trimming and paste applying means, and means for variably positioning said automatic reel.

110 3. In a wall papering machine, means for trimming and applying the paste to the wall paper, and means for suspending and mounting said trimming and paste-applying means, comprising a member having a reel and flexible members adapted to interconnect said reel and said trimming and paste applying means for the suspension of said paste applying means, and means for engagement with the base of said trimming and paste-applying means for mounting said trimming and paste-applying means.

115 4. A wall papering machine, comprising an

120

125

elongated tubular supporting post adapted to be mounted in variable positions as desired, a support positioned on said post having a stud for engagement in the hollow thereof, and trimming and paste applying means positioned on said support, said stud having means cooperable therewith for releasing said stud for movement to an adjustable position and for retaining said stud in fixed relation to said post when moved to adjusted positions.

5. A wall papering machine, comprising an elongated tubular supporting post adapted to be mounted in variable positions as desired, a support positioned on said post having a stud for engagement in the hollow thereof, and trimming and paste applying means positioned on said support, said trimming and paste applying means having a guide roll positioned at the top thereof for guiding the wall paper, and means for adjusting said guide roll.

6. In a wall papering machine, means for trimming and applying the paste to the wall paper, and means for variably positioning said trimming and paste-applying means comprising a post adapted to be variably positioned, a rod projecting from said post for suspending the trimming and paste-applying means therefrom, and means for freely supporting said rod from said post comprising an eyelet member through which said rod projects, a saddle for engagement with said rod, and bracket members for supporting said saddle.
